J. CAYLOR

BOX

Filed June 30, 1923

UNITED STATES PATENT OFFICE.

JEFFERSON CAYLOR, OF INDIANAPOLIS, INDIANA, ASSIGNOR TO GENERAL BOX COMPANY, OF CHICAGO, ILLINOIS, A CORPORATION OF DELAWARE.

BOX.

Application filed June 30, 1923. Serial No. 648,733.

This invention relates to boxes, and more particularly to wirebound and similar boxes for shipping purposes.

Among other objects the invention is intended to provide a box of light and strong construction, and one susceptible of certain advantages in manufacture.

An illustrative box containing an embodiment of the invention is shown in the annexed drawings, in which:

Fig. 1 is a perspective view of the unassembled box parts in position about to be assembled,

Fig. 2 is an end elevation of the box showing the lid in open position,

Fig. 3 is a perspective view of the completed box in condition for shipment of contents.

The illustrative box comprises a wire-bound blank folded about end sections or heads.

A rectangular form of box being illustrated, the foldable blank for forming the successive box sides, other than the ends, comprises in this instance four sections 1, 2, 3 and 4. These sections consist of suitable side material, such for instance as wood veneer, attached to end cleats 5, 6, 7 and 8, respectively; and the several sections are flexibly united in cooperative foldable relationship by the binding wires 14, certain of which wires are stapled through the side material to the cleats. In this instance the cleats are shown having mating ends of the well-known mortise and tenon type.

When the blank is folded into box form around the heads 9 and 10, and the continuity of the binding wires is completed by tying or fastening their extremities, as indicated at 13, the cleats of the respective sections cooperate in the usual manner to form approximately rigid cleat frames at the opposite sides or heads of the box, spaced apart and held by the side material and bound by the wire binding and resisting the tension of said binding, as well understood in the art.

By constructing the blank so as to fold with adjacent portions of adjacent side material overlapping one another, on the principle explained in the reissued patent to Inwood and Lavenberg No. 12,725 of November 26, 1907, the binding wires become tensioned in the folding operation over the

dihedral corners of the box, thereby increasing the strength and promoting the tendency of the box to resume its shape after undergoing distorting strains, as for instance when the box is dropped on a trihedral corner.

For strength and lightness of construction, the end sections or heads 9 and 10 of the box consist of sheets of thin rigidifying material, such as sheet metal, which combine the advantages of stiffness and non-frangibility with capacity for flexing under strains and of bending under such severe strains as would disrupt ordinary wooden headed boxes.

These heads are shown having upper flanged ends 11 and correspondingly flanged lower ends 12, formed by bending the ends of the heads at right angles to their body portions. Said flanged ends 11 and 12 provide angle reinforcement at the top and bottom of the box, and serve as attaching flanges for securing the heads to the top and bottom cleats. It will be observed that the heads are so disposed that their opposite side margins bear against the inner faces of the corresponding cleats 6 and 8, while the flanges 12 overlie the bottom cleats 7 and the flanges 11 underlie the top or lid cleats 5, both flanges 11 and 12 extending between the vertical cleats 6 and 8. It will be appreciated that when the heads are so arranged with relation to the cleat frames of the box, the upper and lower ends of the head 9 may be readily secured to the top and bottom cleats from the exterior of the box, thereby contributing to the rigidity of the box.

Viewing the end of the completed box as shown in Fig. 3, the structure of the end section or head 9 and the arrangement of its top and bottom flanges 11 and 12 with relation to the cleats of the cleat frame, produces the effect of a girder extending between vertical cleats 6 and 8, said flanges 11 and 12 forming the top and bottom chords of the girder to brace their contiguous cleats and increase their resistance to distorting strains. This construction is effective in opposing crushing forces as well as diagonal strains exerted upon the box, since such forces and strains would act directly upon the top and bottom chords of the sheet metal girder heads.

For further stiffening and strengthening

effect, and for increasing resistance of the heads to distorting forces, the heads may be suitably corrugated or provided with stamped ribs to form braces, struts or the like, one appropriate form of head for a box of the illustrative form being shown, providing stiffening ribs 15.

In assembling the illustrative box (which may be furnished to shippers as an unfolded shank) the sections 2, 3 and 4 of the foldable blank may be folded about corresponding sides of the sheet metal heads 9 and 10, and the heads may be secured to the cleats 6 and 8 of the sections 2 and 4 by nails or other appropriate fasteners driven from the interior of the box, while the bottom flanges 12 of the heads may then be secured by such fastenings to the bottom cleats 7. After the box is filled, and after the top section or lid 1 is closed and secured by completing the continuity of the wire bindings around the box, the top flanges 11 of the heads may be secured in the same manner to the top or lid cleats 5.

25 Thus the filled and closed box, in condition for shipment of contents, has all of its cleated sections, including the lid, firmly tied together by the heads of the box as well as by the binding wires, and the opposite heads tied together at all sides by cleated sections, which contributes to the strength and rigidity of the package and prevents any bowing or separation of the box sides at unsecured margins, with accompanying exposure and bulging contents. Moreover the construction of the sheet metal heads with top and bottom flanges and the securing of these flanges to the top and bottom cleats by fastenings driven in a plane transversely of that of the fastenings of the side margins of the heads to the cleats 6 and 8, further increases the rigidity of the box and its resistance to distorting strains.

45 The illustrative box is a comparatively deep narrow box adapted for shipment of such articles as cans of motor lubricating oil; and the construction described is admirably adapted to provide a strong and efficient box of this type. Furthermore the bottom flanges of the sheet metal heads provide convenient means for attachment of the heads to the bottom cleats, to which it would be ordinarily somewhat inconvenient to secure the heads by fastenings driven from the interior in such a deep narrow box. Thus the 50 illustrative box typifies a construction having sheet metal heads appropriately flanged to provide angle reinforcement suitable to the form and dimensions of the box, and 55 for attachment of the heads to such of the cleats as could not be conveniently secured

by fastenings driven from the inside, in this instance the top and bottom cleats.

The girder-like sheet metal box heads further contribute an element of elasticity to 65 the box, and cooperate with the wire bindings in flexibly resisting distorting strains and tending to restore the box to its original shape after relief from such strains. For instance, if the box should be dropped 70 upon a trihedral corner, or subjected to diagonal strain, the cleated sides of the box may flex or shift relatively to one another, with accompanying flexure of the binding wires and the metal ends of the box; while the 75 tension of the binding wires and the resiliency of the heads will cooperate in resisting such flexing and in restoring the box to its original form after the strain is relieved.

80 Boxes of the construction described may be manufactured with somewhat smaller dimensions than ordinary wooden headed wire-bound boxes, without sacrificing the capacity of the box. In other words, by virtue of the thin material employed for the heads, 85 boxes of specified interior dimensions may be made with shorter sections of material for the foldable cleated sides of the box. This materially contributes to lightness of construction and results in a considerable saving 90 of material in the manufacture of such boxes on a large commercial scale, and an appreciable gain is made in the storage of such boxes in large quantities. Furthermore, such boxes possess unusual strength 95 and rigidity, combined with an unusually great elastic limit, promoting the capability of the box to endure rough usage.

It will be obvious that the present invention is not limited to the specific details of 100 construction of the illustrative box, since the same may be variously modified to suit the different forms and dimensions of boxes required for various shipping purposes.

Having described an embodiment of my 105 invention, I claim:

A wirebound box of deep and narrow form comprising, in combination, sheet metal heads having top and bottom flanges; and a foldable cleated blank folded about said 110 heads; the vertical margins of said heads abutting against and being secured to the vertical cleats of the blank by fastenings driven from the interior of the box; and the top and bottom flanges of said heads being 115 secured to the top and bottom cleats of the box by fastenings driven from the exterior, said flanges extending substantially the full distance between the vertical cleats.

In testimony whereof, I have signed my 120 name to this specification.

JEFFERSON CAYLOR.
